MEANS FOR TIMING LOOP-TAKERS OF
SEWING MACHINES

Alfred R. Wood, Bridgeport, Conn., assignor to
The Singer Manufacturing Company, Elizabeth, N. J., a corporation of New Jersey

Application September 4, 1944, Serial No. 552,580

1. Claim. (Cl. 112—220)

This invention relates to sewing machines and more particularly to sewing machines in which the loop-taker operates in a circular path and cooperates with a reciprocating eye-pointed needle. In sewing machines of this kind, it is essential to the perfect functioning of the machine that the beak of the loop-taker be accurately timed relative to the needle to insure that the beak enters the needle loop during each stitch-forming cycle, thereby to avoid defective stitching.

One of the objects of this invention is to provide an improved means for varying the position of the beak of the loop-taker in its orbital path, thereby properly to time the loop-taker beak relative to the reciprocating needle.

Another object of this invention is to provide a simple and inexpensive device for accurately varying the timing of the loop-taker relative to the needle and in which the device for varying the timing of the loop-taker acts as a counter-balance to reduce vibration of the machine.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings,

Fig. 1 is a front elevation, partly in section, of a buttonhole sewing machine having my invention embodied therein.

Fig. 2 is an enlarged sectional view taken substantially along the line 2—2 of Fig. 1.

Fig. 3 is an enlarged sectional view taken along the line 3—3 of Fig. 1.

Fig. 4 is an enlarged sectional view taken along the line 4—4 of Fig. 1.

Fig. 5 is a side elevation, and Fig. 6 is a top plan view of the member used to vary the timing of the loop-taker relative to the needle.

In the embodiment of the invention selected for illustration, the invention is shown applied to a buttonhole sewing machine comprising a frame including a bed 10 from one end of which rises a standard 11 carrying an overhanging bracket-arm 12 which terminates in a hollow head 13. Journaled in the bracket-arm 12 is a rotary needle-bar shaft 14 driven by means of gears 16 and pulleys 15, which may be operatively connected through a belt to any suitable source of power. The other end of the needle-bar shaft

14 carries a crank 17 which is connected by means of a link 18 to the usual reciprocating needle-bar 19 carrying an eye-pointed needle 20.

Journalized in suitable bearings beneath the bed 10 is a hook carrying shaft 21 having fixed to one of its ends a rotary hook 22 which is adapted to cooperate with the reciprocating needle 20 in the formation of lock stitches. Secured to the hook-shaft 21 and located beneath the standard 11 is a gear 23 which meshes with a gear 24 secured to the lower end of a vertical shaft 25 journalized in bearings 26 located within the hollow standard 11. To the upper end of the shaft 25 there is secured a second bevel gear 27 which meshes with a gear 28 carried by the needle-bar shaft 14. The ratio of the gearing between the shafts 14 and 21 is as 1 is to 2 and, therefore, the shaft 21 makes two complete rotations for each complete rotation of the needle-bar shaft 14.

From the foregoing, it will be understood that the needle 20 reciprocates and the hook 22 rotates in timed relation with the needle. In some instances it is necessary to change the timing of the hook relative to the needle and in order to simplify the hook timing and thereby permit mechanics in the field readily and easily to time the hook relative to the needle, I have provided a member 30 formed with a circular opening 31 which is adapted to receive the shaft 14. The member 30 abuts the hub 34 of the gear 28 and is fixed to the shaft 14 by the set screw 32 and pin 33.

The member 30 is formed with two spaced laterally extending ears 35, 36 which are adapted to overlie the hub 34 of the gear 28. The ears 35, 36 are provided with complementary set-screws 37, 38 which cooperate with a screw 39 carried by the hub 34 of the gear 28, the screw 39 being located between the spaced ears 35, 36.

With the above described construction, the rotary hook 22 may be adjusted or timed relative to the needle 20 in the following manner. The screws 39 and 40 which secure the gear 28

45 to the shaft 14 are "backed off" just enough to free the gear 28 from the shaft 14. Depending upon the direction it is decided to shift the hook 22 relative to the needle, one of the screws 37 or 38 is "backed off" a slight amount and the other screw is screwed in until the desired position of the hook-beak relative to the needle is obtained. The first mentioned screw is then screwed in until it engages the shank of the screw 39. The screws 39 and 40 are then tightened to further lock the gear 28 to the shaft 14.

From the above description it will be understood that a micrometer adjustment for varying the timing of the hook relative to the needle has been provided and that the hook may be adjusted relative to the needle from a point above the bed plate. It will also be understood that a careful and accurate adjustment may be readily and easily made without the necessity of turning the machine upside down or on its side for the purpose of gaining access to the hook, and that it is not necessary to loosen the hook 22 on its shaft and then turn the hook as has been the practice heretofore. It will be observed that the member 30 together with the ears 35, 36 are shaped to form a counterbalance which is utilized to balance the actuating mechanism and thus reduce vibration.

From the foregoing description it will be apparent that my hook timing device may be located on the hook-shaft as well as the needle-bar shaft and that the construction disclosed is susceptible of other variations. Therefore, the

privilege is reserved of resorting to all such legitimate changes therein as may be fairly embodied in the spirit and scope of the appended claim.

Having thus set forth the nature of the invention, what I claim herein is:

A sewing machine having in combination, a frame comprising a bed-plate and an overhanging bracket-arm, a hook-shaft journaled beneath said bed-plate, a needle-bar actuating shaft journaled in said bracket-arm, a gear carried by said needle-bar shaft and formed with a hub, a member fixed to said shaft and having spaced laterally extending ears which overlie said hub, a screw carried by each of said ears, said screws being in alignment and adapted to engage a stud projecting radially from the hub of said gear for the purpose of adjusting said gear circumferentially on said needle-bar shaft, and gearing operatively connecting said first mentioned gear with the hook shaft.

ALFRED R. WOOD.
